UNITED STATES PATENT OFFICE.

THOMAS PETER EUSTEDE, OF HATAITAI, WELLINGTON, NEW ZEALAND.

RETAINER FOR DOORS AND WINDOWS.

1,177,026.

Specification of Letters Patent. Patented Mar. 28, 1916.

Application filed August 25, 1915. Serial No. 47,303.

To all whom it may concern:

Be it known that I, THOMAS PETER EUSTEDE, a subject of the King of Great Britain and Ireland, and residing at Hohiria Road, 5 Hataitai, in the city of Wellington, in the Dominion of New Zealand, have invented a new and useful Improvement in Retainers for Doors and Windows; and I do hereby declare the following to be a full, clear, and 10 exact description of the same.

The object of this invention is to provide improved means for retaining doors and windows at any desired position.

The device consists essentially of a slide 15 fastened to the door or window frame at a suitable position. A block is slidable upon the slide and has pivoted thereto a shank which is also pivoted at a suitable point, in the case of a door, to the architrave or to 20 the wall, and in the case of a window, to the window sash. Within the block a tension plate under pressure of a spring is adapted to bear upon the slide. A nut or pin having a knurled or milled head is threaded into 25 the block and the spring is in compression between the tension plate and the nut. By means of the nut the tension upon the tension plate is adjusted to the required pressure.

30 In the case of the application of the invention to doors a spring may be provided whereby the door will be caused to return to its closed position.

The drawings illustrate the invention 35 wherein:

Figure 1 is a view of a door with the invention applied thereto. Fig. 2 is a sectional plan of the door. Fig. 3 is a cross section through the slide and sliding block. Fig. 4 40 is a plan of the sliding block. Fig. 5 is a plan and Fig. 6 a part sectional plan of the invention having a spring for returning the door to its close position. Fig. 7 is a plan of a retainer applied to a casement window. Fig. 8 is a sectional plan and Fig. 9 is an 45 elevation of the invention applied to a casement window. Fig. 10 is a side view and Fig. 11 a front view of the fastening device used in connection with the device shown in 50 Figs. 8 and 9. Fig. 12 is a section through line A—A Fig. 10.

Referring to the drawings and first to Figs. 1 to 4 a member which forms a slide 1 is fastened horizontally to the interior side 55 of the door 2 preferably at a position as shown in Fig. 1. The slide 1 may be of the

shape shown in section in Fig. 3 while a member or block 3 has flanges 4 adapted to engage over the flange 5 of the slide 1. An integral boss 6 projects outwardly from the 60 block 3 and has a hole 7 throughout its length. A nut or pin 8 having a milled head 9 is threaded into the hole 7 while a coil spring 10 is in compression between the end of the nut 8 and a tension plate 11 resting 65 upon the face of the slide 1 as clearly shown in Fig. 3. The end of a shank 12 is pivoted by a pin 13 in lugs 14 integral with the block 3. The other end of the shank 12 is pivoted in a bracket 15 fixed to the architrave or to the wall. By operating the nut 8 the pressure of the tension plate 11 upon 70 the face of the slide 1 may be increased or decreased. When the tension of the plate 11 upon the slide is only slight the plate will 75 make a frictional contact with the slide under the influence of the spring 10 sufficient to prevent the door from moving on slight pressure and eliminate slamming of the door. As the door is opened the block 3 slides along 80 the slide 1 and assumes the position shown in dotted lines in Fig. 2.

In Figs. 5 and 6 the slide 1 consists of a cylindrical tube 16 having the block 3 sliding upon it as already described with reference to Figs. 1 to 4. The tension plate 11 conforms to the contour of the cylindrical slide and has attached to it one end of a coil spring 17, the other end of which is fastened to the slide at 18. A slot 19 is provided in 85 the cylindrical slide through which slot the end of the spring 17 projects into the plate 11 and which allows the block 3 to move 90 along the slide 1.

The block in Figs. 5 and 6 is shown in 95 the position it assumes when the door is closed. When the door is opened the block moves along the slide in the direction of the arrow in Fig. 5 thus extending the coil spring 17. The tension of the spring will 100 tend to draw the block back to its normal position thus closing the door. The pressure of the tension plate 11 upon the slide will, however, prevent the block from being drawn too rapidly along the slide thus the 105 door is prevented from slamming.

By adjusting the nut 8 as before described the required tension is placed upon the plate 11 and if desired sufficient tension may be placed upon the said plate to hold the door 110 in any desired position.

Figs. 7 to 12 show the application of the

invention to casement windows. In Fig. 7 the slide 1 is attached to the sill 21 of the window frame while the shank 12 is pivoted in a bracket 22 fixed to the bottom rail of the sash 23. In Figs. 8 and 9 the slide 1 is tubular and is fixed to a vertical side 24 of the window frame. The shank 12 is pivoted at one end in the sliding block 3 as hereinbefore described while the other end 10 of the shank is pivoted to a short arm 25 which is in turn pivoted to a bracket 26 fixed to the rail 27 of the sash at about the middle thereof. The short arm 25 allows the shank to follow the radial movement of the window sash. When the sash is closed the shank 12 assumes the position shown in Fig. 9. The nut 8 is then tightened and the tension plate 11 is brought to bear tightly upon the surface of the slide thus retaining 20 the sash in position. The slide 1 being cylindrical allows the block 3 to rotate upon it thereby allowing for the radial movement of the sash. The sash may be held in any desired open position by tightening the nut 25 8. When the sash is closed a finger 29 projecting from the short arm 25 is adapted to engage over a projection 30 in a bracket 31 fixed to the vertical frame 24 (see Figs. 10 and 11). The side of the finger 29 is provided with a sloping face 32 (see Figs. 10 and 12) against which the conical point of a pin 33 having a milled head 34 is adapted to engage. The pin 33 is threaded into the bracket 31 as shown and upon the pin being 35 tightened the finger is drawn into the bracket and the sash thereby brought tightly to bear against the window frame.

What I claim is:

1. In a retainer of the kind described, a 40 tubular slide fixed to the interior side of the door, a block slidable upon said slide, a tension plate within said block and bearing upon

the said slide, a spring attached at one end to the said tension plate and the other end of said spring fixed to the said slide, means 45 for adjusting the tension of said tension plate upon said slide, and means for allowing said block to slide along said slide substantially as set forth.

2. In a retainer of the kind described, 50 the combination of a tubular slide having a longitudinal slot therein; a block embracing the slide and having a hole therein; a tension plate in said hole; and a spring having one end secured to the slide and the other end passed through said slot and secured to the tension plate.

3. In a retainer of the kind described, 55 the combination of a tubular slide having a longitudinal slot therein; a block embracing the slide and having a hole therein; a tension plate in said hole; a spring having one end secured to the slide and the other end passed through said slot and secured to the tension plate; a spring in said hole pressing on said tension plate; and a set screw pressing on said last named spring; and a shank pivoted to the block.

4. In a retainer of the kind described, 70 the combination of a tubular slide having a longitudinal slot therein; a block embracing the slide and having a hole therein; a spring in said slide and having one end adapted to exert a pull on the slide and the other end passed through said slot and attached to the block; a set screw in said hole and a shank pivoted to the block.

In testimony whereof, I have signed my name to this specification in the presence of two subscribing witnesses.

THOMAS PETER EUSTEDE.
